COMBINED CIGARETTE AND MATCH PACKAGE

Masamitsu Ishihara, 628 Hirai, Kannami-cho,
Tagata-gun, Shizuoka-ken, Japan

Original design application Mar. 15, 1973, Ser. No.
341,582. Divided and this application Oct. 11,
1974, Ser. No. 514,011

Term of patent 14 years

Int. Cl. D9—03

U.S. Cl. D9—193

FIG. 1

FIG. 4

FIG. 1 is a top, front perspective view of a combined cigarette and match package showing my new design, with the match flap partially opened;

FIG. 2 is a bottom rear perspective view thereof;

FIG. 3 is a side elevational view thereof; and

FIG. 4 is a view similar to FIG. 1 but with the match flap fully opened.

This is a division of co-pending application Ser. No. D. 341,582, filed Mar. 15, 1973.

I claim:

The ornamental design for a combined cigarette and match package, as shown and described.
